E. I. STAPLES

FUEL OIL HEATER

Filed May 5, 1923

Earle I. Staples,
INVENTOR

BY *Victor J. Evans,*

ATTORNEY.

Patented Mar. 10, 1925.

UNITED STATES PATENT OFFICE.

EARLE I. STAPLES, OF NEW YORK, N. Y.

FUEL-OIL HEATER.

Application filed May 5, 1923. Serial No. 637,036.

To all whom it may concern:

Be it known that I, EARLE I. STAPLES, a citizen of the United States, residing at New York city, in the county of New York and State of New York, have invented new and useful Improvements in Fuel-Oil Heaters, of which the following is a specification.

This invention relates to fuel oil heaters and has for its primary object the provision of means for creating an oil film and for placing same in circulation while subjecting the oil to the action of a heating agent and for correlating the agent and the oil, to heat the latter in a highly effective manner.

15 A further object of the invention is to provide means for subjecting the oil to the maximum action of a heating agent and to quickly heat the oil while causing a circulation of the oil in a structure which automatically acts to relieve the oil of dirt, sand 20 and water that precipitates from heating the oil.

Another object of the invention is to provide a heater of the character which may 25 be subjected to a cleaning process without the necessity of throwing the heater out of operation at such time.

With these and other objects in view, the invention resides in certain novel construction and combination and arrangement of parts, the essential features of which are hereinafter fully described, and particularly pointed out in the appended claims, and are illustrated in the accompanying drawing, in which:

Figure 1 is a longitudinal section through the heater showing same associated with an oil pump, the latter being in elevation.

Figure 2 is a transverse section through the heater showing the pump in elevation.

Figure 3 is a diagrammatic sectional view of the drum showing a slightly modified form thereof.

In carrying the invention into practice, I 45 employ a cylindrical drum 10 provided with upper brackets 11, 11 and lower brackets 12, 12, the latter adapted to constitute supporting feet for the drum whereby it may be firmly anchored to a floor or other suitable 50 support. The brackets 11 are connected with a metallic tray 13 on which a pump mechanism 14 is supported and adapted to force steam into the heater in a manner to be hereinafter described.

55 The drum is provided with concentric cylinders 15, 16, 17 and 18, the ends 19 of which

are preferably welded to the interior of the head 20 of the drum. The cylinder 15 has its end adjacent to the head 21 of the drum curved inwardly at 22 and welded at 23 to the adjacent end of the cylinder 16. The cylinders 15, 16, 17 and 18 are preferably equi-distantly spaced apart and as illustrated the cylinders 17 and 18 are somewhat longer than the aforesaid cylinders 15 and 16. The said cylinder 17 has its end 24 adjacent to the head 21 of the drum curved inwardly and welded at 25 to the cylinder 18. The said head 21 of the drum 10 is spaced from the adjacent ends of the aforesaid cylinders 15, 16, 17 and 18. By arranging these cylinders in pairs it will be observed that concentric chambers 26 and 27 are formed thereby and that these chambers are respectively of different lengths. The 75 inner cylinder 18, aside from its association with the cylinder 17 to form the chamber 27 is also designed to constitute a discharge duct 28 for a purpose to be hereinafter described and to allow for expansion and contraction.

Welded internally at 29 to the head 21 of the drum 10 is a cylindrical baffle wall 30. This wall extends for approximately two-thirds the length of said drum 10 and is 85 open at 31 so as to communicate with the circulating space 32 between the cylinders 16 and 17.

Leading from the pump mechanism 14 is an oil delivery nozzle 33 which is associated with a valve 34 so that oil in regulated proportions can be discharged to the drum. This nozzle preferably extends through the head 21 and toward the opposite head 20 and is interposed in the circulating space 35 between the walls of the drum and the adjacent cylinder 15. The discharge end of the nozzle is spaced for a suitable distance from the head 20 so that as oil emerges from the nozzle it is brought into impingement with said head 20 and then converted into a film which circulates in a sinuous manner over the respective surfaces of the cylinders 15, 16, 17 and 18 and the baffle wall 30 so that incident to the 100 relation of said baffle wall to the cylinders 16 and 17, the oil finally flows into the discharge duct 28. Extending into this discharge duct 28 from the head 21 is a discharge pipe 36 connected exteriorly of the 105 drum with a strainer 37. This strainer is provided with a pipe connection 38 adapted

to be operatively associated in the usual well-known manner with a burner, not shown.

Leading from the pump mechanism 14 is a steam pipe 39 having nozzles 40 and 41 respectively of varying lengths. These nozzles pass through the head 20 and into the respective chambers 26 and 27 so that steam may be introduced into the chambers 10 from a point above the horizontal axis of the drum. At a point below the horizontal axis of the drum are connections 42 and 43 which are both connected with an exhaust pipe 44 so that exhaust steam and water of condensation can be taken off from the heating chambers.

The drum is provided with a valved drain connection 44 adapted to permit of the drawing off sediment from the drum while the heater is in operation. This drain valve also permits water of condensation to be discharged from the drum as desired.

Due to the relative arrangement of parts aforesaid it follows that the heater acts as a filter or trap and that the same automatically catches sand or other sediment and water which being heavier than oil, precipitates to the bottom of the drum where it is held against passing through the discharge pipe 36. It will be understood that when the delivery pipe 33 is connected with the pump, pressure will be created in this pipe to induce circulation of oil in the heater and an effective discharge of the heated oil in operative time with a thorough heating of the oil.

In operation oil flows in one direction into the drum and it is first caused to enter the space 35. It is converted into a film and is forced in a like manner over the surfaces of the respective cylinders 15, 16, 17 and 18 and the baffle wall 30, taking a sinuous course and finally entering the discharge duct 28. The steam is forced into the chambers 26 and 27 from the opposite ends of the drum and the steam initially flows in an opposite direction to that of the oil as it comes from the pipe 33. This method of introducing steam to the chambers 26 and 27 serves to effectively heat the cylinders 15, 16, 17 and 18 and cause the thin film of oil to be thoroughly subjected to the action of heat through contact with said cylinders. The steam is held out of direct contact with the oil and by causing the oil to be discharged from an opposite point to that of the steam, the highest heating efficiency of the oil results. I also find that by the use of chambers 26 and 27 of respectively varying lengths, combining them with steam nozzles 40 and 41 also of varying lengths, I am able to effectively heat the surface of the cylinders 15, 16, 17 and 18 at different points in the course of travel of the oil. In other words, steam

flowing in one direction and the oil flowing in an opposite direction creates a counter-flow principle which allows the oil to first pass over the hottest portions of the cylinders.

As previously stated it will be observed that while a body of oil is being heated, the heater also acts as a filter and settling chamber for all dirt, sand and water which precipitates from heating the oil, which can be blown off while the system is in use, thus rendering the heater self-cleaning.

By welding the steam chambers to the interior of the head 20 of the heating drum at one end and spacing the opposite ends of the chambers from the head 21 and associating said chambers with a baffle wall 30 having only one of its ends permanently secured in the drum, it follows that said chambers and said baffle wall are free for relative movement due to the action of expansion and contraction and without liability of the parts being ruptured in any manner that might cause leakage.

The drum 10^a shown in Figure 3 is associated with a pipe 36^a whose ends are welded at 20^a and 21^a to the respective heads of the drum. The pipe is provided with radial oil intake perforations 36^b. In this form, the welding of the pipe to the heads of the drum braces the latter and constitutes reinforcing means therefor.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:—

1. An oil heater comprising a drum having internal chambers therein of graduated lengths, said chambers spaced apart, one of the chambers formed with an oil discharge duct, means to conduct heated oil from said duct, means for introducing oil to the drum from one end of the latter, means for introducing steam to the chambers from the opposite end of the drum, and means associated with said chambers to cause a film of oil to circulate over the walls of the chambers and finally escape to said discharge duct.

2. An oil heater comprising a drum having chambers therein arranged therewithin and out of communication with each other, means for subjecting the chambers to the action of a heating agent, the said chambers terminating in spaced relation to one end of the drum, a baffle wall extending from said one end of the drum and co-acting with the walls of the chambers to cause a film of oil to travel in a sinuous course, one of said

chambers having a discharge duct for the operative reception of the heated oil, means to permit the oil to be taken off from said duct, and means for delivering oil to the drum in the operative presence of said chambers to cause the oil to be subjected to the action of heat from said chambers.

3. A heater comprising a drum having steam chambers therein of respectively varying lengths, the walls of which are relatively positioned to define an oil circulating space therebetween, means separating the chambers to cause the oil to take a sinuous course through the drum, one of the chambers having its walls formed to constitute a duct in communication with the aforesaid circulating space, means for delivering oil to the drum from one end thereof, means for delivering steam to the chambers from a point at the opposite end of the drum, and means to permit heated oil to be discharged from said drum.

4. An oil heater comprising a drum, a plurality of concentric spaced steam chambers therein extending in the length of the drum and each welded at one end to one head of the drum exteriorly thereof and spaced at its opposite end from the other head of said

drum, the inner chamber having a discharge duct, a baffle wall concentric with said chambers and secured at one of its ends to said other head of the drum, means for delivering oil to said drum the walls of the chambers co-acting with said baffle wall to cause the oil to flow in a sinuous manner through the drum and to pass to said discharge duct, and means to permit the heated oil to be conveyed from said duct.

5. An oil heater comprising a drum having chambers therein secured to one head thereof and a co-acting baffle wall secured to the opposite head of said drum to permit said baffle wall and said chambers to move relatively due to the action of contraction and expansion of the parts, the baffle wall and said chambers co-acting to cause oil to pass into the chamber and flow over the external walls of the chambers and across the walls of the baffle, the said drum having an outlet connection co-acting with the aforesaid parts to permit the heated oil to pass from said drum.

In testimony whereof I have affixed my signature.

EARLE I. STAPLES.
